STOCK WATERING TANK

Clem Fine, Braddyville, Iowa

Application January 19, 1945, Serial No. 573,570

3 Claims. (Cl. 119—73)

1

This invention relates to a watering tank for livestock, and more particularly to such a tank adapted to be utilized on farms, ranches, and the like.

A primary object of this invention is the provision of an improved stock watering tank, having integral therewith a built-in heater, whereby the water in the tank may be kept from freezing regardless of the temperature.

Another object of this invention is the provision of a tank having a heater therein, wherein the fuel is fed to the heater from the exterior of the tank, below the water level, thus precluding the possibility of contamination of the water in the tank from fuel dropping thereinto.

Still another object of the invention is the provision of such a tank wherein the heater is completely submerged in the water, and consequently requires little heat and creates a circulation of the warm water through the cold water in the upper portion of the tank at all times.

A still further object is the provision of such a device adapted to utilize any suitable fuel, such as may be conveniently found around a feed lot on a farm or the like.

A still further object is the provision of such a tank of welded construction, wherein the seams are welded on the exterior of the tank to permit expansion of the same, should it be undesirable to keep a fire in the tank at all times, and the water allowed to freeze.

A further and more specific object of the invention is the provision of an auxiliary tank in conjunction with the main tank wherein the water is at a lower level, in such a manner that the smaller stock, such as pigs, fowl and the like, may utilize the same tank.

Another more specific object is the provision of valve means in association with such an auxiliary tank to maintain the water therein at a desired predetermined level.

A still further object is the provision of such a device which will be sturdy and durable in construction, reliable and efficient in operation, and relatively simple and inexpensive to manufacture and assemble.

Other objects reside in the combinations of elements, arrangements of parts, and details of construction, all as will be more fully pointed out hereinafter and disclosed in the accompanying drawings, wherein there is shown a preferred embodiment of this inventive concept.

In the drawings:

Figure 1 is a perspective view of one form of tank embodying the instant invention.

2

Figure 2 is an end elevational view of the structure shown in Figure 1, certain parts thereof being broken away.

Figure 3 is a front elevational view, partially shown in section, certain parts thereof being broken away.

Figure 4 is a top plan view of the device.

Figure 5 is a view taken from the rear of the device, shown partially in section and partially in elevation.

Figure 6 is a sectional view taken substantially along the line 6—6 of Figure 4, as viewed in the direction indicated by the arrows, and

Figure 7 is a fragmentary detail sectional view, partially broken away, showing certain portions of the operating mechanism.

Like reference characters refer to like parts throughout the several views of the drawings.

Having reference now to the drawings, there is generally indicated at 10 the tank of the instant invention, which is comprised of end walls 11 and 12, side walls 13, a base 14, and a top generally indicated at 15.

The bottom and side and end walls are preferably secured together, as by welded seams, including flanges 16 at each of the joints thereof welded together along their outer extremities, in such manner as to permit limited expansion of the tank, should freezing of the water therein occur, for any reason.

Referring back to the top member 15, it will be seen that the same is comprised of a central section 17 and two side sections 18, each of which is formed with an arcuate flange 19, through which extends a rod or the like 20 adapted to engage in opposite aligned brackets 21 on the central section 17 at the extremities thereof, in such manner that each of the sections 18 is hingedly secured to the section 17. Flanges 22 are provided about the edges of sections 18 in order to afford finger grips for raising the same. Thus, it will be seen that access may be had to the tank by raising either or both of the members 18.

Extending transversely through a mid portion 45 of the device from the front wall 11 to the rear wall 12, and passed through suitable apertures in both of these walls, is a tubular member 25 having an intermediate partition 26 positioned a spaced interval from front wall 11.

A smokestack, or the like, 27 is secured between the partition 26 and the rear wall 12, and extends upwardly through a suitable aperture in the portion 17 of the cover 15, and terminates in a suitable cap 28 adapted to deflect rain or snow, or 55 the like, therefrom. A damper 29 is positioned in

a suitable point in the smokestack above the cover 15. The portion of the tubular member 25 between partition 26 and rear wall 12 constitutes the fire box of the device, and is closed by a suitable door 30 hinged, as at 31, and provided with a latch 32 engageable in a suitable bracket 33 positioned adjacent thereto on rear wall 12. A rotatable damper 35 provided with apertures 36 is positioned at a suitable point in the door 30.

The lower portion of the end of the tubular member 25 extending through the front wall 11 is closed by a partition 37 to provide an auxiliary water tank for smaller livestock, such as pigs or fowl, or the like.

As best shown in Figures 7 and 3, a pipe 40 extends through the wall of tubular member 25 into the tank 10 to permit the auxiliary tank to be filled therefrom. The level of the water in the auxiliary tank is controlled by means of a float valve comprised of a float member 41 having a stem 42 curved at right angles thereto and pivotally secured, as at 43, to a member secured to the extremity of the pipe 40. A loop 44 in the stem 42 engages a second stem 45 which extends through the pipe 40, and terminates in a plug or cork 46 on the interior of the tank 10. Thus, it will be seen that when the water level in the auxiliary tank rises above a predetermined point, the float 41 will be raised drawing the plug 46 into the end of the pipe 40 effectively to close the same. Conversely, as the water level drops, the float 41 will sink forcing the plug 46 outwardly, and permitting replenishment of the supply in the auxiliary tank.

From the foregoing, the operation of the device should be readily apparent. When it is desired to heat the water in the tank, a fire is started in the tubular member 25, fuel being inserted through the door 30, and the draft of the blaze controlled by the dampers 29 and 35. Inasmuch as the water in the main tank 10 completely surrounds the tubular member 25, it will be seen that normal thermal currents are sufficient to circulate the body of water in the tank and retain the same at a suitable desired temperature to preclude freezing of the same. The water in the auxiliary tank, the level of which is controlled by the float 41 in the manner previously described, being adjacent the partition 26 which closes the fire box portion of the tubular member 25, is likewise maintained at a constant temperature above freezing.

Now, from the foregoing it will be seen that there is herein provided an improved stock watering trough accomplishing all the objects of this invention and others including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A stock watering tank comprising, a main tank, a tubular sleeve member extending therethrough and spaced above the bottom of said tank, said tube having an intermediate partition forming two chambers therein and both ends of said tube being open, a door closing an end of the tubular member and one of said chambers and defining therewith a fire box, a partition closing the lower portion of the other end of the tubular member and the other chamber and defining therewith an auxiliary tank, and a chimney extending directly upwards from said fire box, through said main tank and discharging to the atmosphere.

2. A stock watering tank comprising, a main tank, a tubular sleeve member extending therethrough and spaced above the bottom of said tank, said tubular member having an intermediate partition forming two chambers therein, and both ends of said tube being open, a door closing an end of the tubular member and one of said chambers and defining therewith a fire box, a partition closing the lower portion of the other end of the tubular member and the other chamber and defining therewith an auxiliary tank, and a chimney extending directly upwards from said fire box, through said main tank and discharging to the atmosphere, and a horizontally extending passage connecting said main tank and said auxiliary tank and provided with automatic valve means controlling flow of fluid therethrough.

3. A stock watering tank comprising, a main tank, a tubular sleeve member extending therethrough and spaced above the bottom of said tank, said tubular member having an intermediate partition forming two chambers therein, and both ends of said tube being open, a door closing an end of the tubular member and one of said chambers and defining therewith a fire box, a partition closing the lower portion of the other end of the tubular member and the other chamber and defining therewith an auxiliary tank, and a chimney extending directly upwards from said fire box, through said main tank and discharging to the atmosphere, and a horizontally disposed communication through a lateral wall of said auxiliary tank and said main tank, a valve means disposed in said main tank, a float means disposed in said auxiliary tank and actuating means operatively connecting said float and valve to control the level of the water in the auxiliary tank.

CLEM FINE.
